UNITED STATES PATENT OFFICE

GUSTAVE A. JOHNSON, OF IRVINGTON, NEW JERSEY, ASSIGNOR TO AMERICAN METAL
MOLDING CO., A CORPORATION OF NEW JERSEY

ARMORED ELECTRIC CABLE

Application filed September 20, 1926. Serial No. 136,461.

This invention relates, generally, to an improved construction of armored electric cable for use in electric wiring installations.

This invention has for its principal object 5 to provide a novel construction of armored electric cable, the electric conductors of which are provided with an inexpensive but nevertheless highly efficient arrangement and relation of insulation mediums combined together 10 in a novel form and manner, to the end that each conductor is adequately separated electrically from the other, while being at the same time united in a single cable structure possessing the desired degree of flexibility, 15 especially suitable for enclosure within flexible metallic armor; the relation of the combined insulation mediums being such that the cable may be readily flexed or bent without risk of rupture or other injury detrimental 20 to the necessary electrical segregation and separation of the conducting wires enclosed therein.

Other objects of this invention, not at this time more particularly enumerated, will be 25 clearly understood from the following detailed description of the same.

The invention is clearly illustrated in the accompanying drawing, in which is shown an embodiment of this invention in the form 30 of a two wire cable, each wire being insulated from the other and at the same time united in cable form by the novel arrangement and relation of combined insulation mediums, and the whole enclosed in flexible metallic armor, 35 all according to the principles of this invention; and in said drawing various portions of the combined insulation mediums are shown progressively broken away to disclose the individual elements and the combined relation 40 thereof one to the other.

Referring to said drawing, the reference character 1 indicates one metallic wire or electric conductor and 2 indicates another such wire or conductor; said wires or conductors are ordinarily made of copper, one serving 45 as a delivering line of an electric circuit and the other as a return line thereof.

The wires or conductors 1 and 2 are each provided with an inner covering of rubber 50 insulations 3. Each wire or conductor is

provided, over the body of rubber insulation 3, with an inner wrapping of paper 4. This inner paper wrapping 4 is preferably of flat strip form spirally wound in one direction, e. g. from left to right, about the entire 55 length of the wire or conductor. It is preferable to provide the surface of the rubber insulation, prior to the application thereto of the inner paper wrapping 4, with a coating 5 of a non-drying and non-hardening tacky 60 substance having adhesive qualities, such as asphaltum, thus assuring a close bond between the wrapping 4 and the rubber coated wire conductor, and eliminating air spaces or pockets therebetween. After the inner 65 paper wrapping 4 is thus applied to each rubber coated wire or conductor, or during the operation of so applying the same, the outer surface of said inner wrapping 4 is coated with a covering layer 6 of a suitable 70 non-drying and non-hardening tacky substance, such as asphaltum, whereupon a second or outer wrapping of paper 7 of flat strip form is applied over the inner paper 75 wrapping 4. This outer paper wrapping is also spirally wound, but in an opposite direction, e. g. from right to left, about the entire length of the wire or conductor, and so that the convolutions of said outer paper wrapping 7 will run substantially crosswise of the convolutions of said inner paper wrapping 4. 80

After the respective wires or conductors 1 and 2 have received the primary insulation elements arranged and combined therewith in the manner above described, the same are 85 laid together in side by side relation, whereupon an inner enveloping wrapping of paper 8 is applied in common to the laid together conductors. This inner enveloping paper wrapping 8 is preferably of flat strip form 90 spirally wound in one direction, e. g. from left to right, and preferably in such manner that its convolutions cross the convolutions of the outer paper wrappings 7 of the primary insulation of said respective conductors. Before or during the application of said inner enveloping paper wrapping 8, the laid together conductors are provided with a coating 9 of a non-drying and non-hardening tacky substance having adhesive qualities 95 100

ties, such as asphaltum, thus assuring a close bond between the inner enveloping paper wrapping 8 and the said primary insulation of the laid together conductors, 5 while at the same time eliminating air spaces or pockets therebetween. After the inner enveloping wrapping of paper 8 is applied as above described, or during the operation of so applying the same, the exterior 10 surface of said wrapping 8 is coated with a covering layer 10 of a suitable non-drying and non-hardening tacky substance, such as asphaltum, whereupon an outer enveloping wrapping of paper 11 of flat strip form is applied over said inner enveloping wrapping 8. This outer enveloping wrapping 11 is also spirally wound, but in an opposite direction, e. g. from right to left, and so that its convolutions run substantially crosswise of the convolutions of said inner enveloping paper wrapping 8. The inner and outer enveloping paper wrappings, together with the intervening coatings of asphaltum, provides a secondary insulation common to both of the conductors 1 and 2.

After the conductors 1 and 2 are thus provided with their individual primary insulation and the secondary insulation common to both, whereby they are united in desired flexible cable form, a suitable metallic armor 12 is applied thereto in the usual manner familiar to those skilled in the art. Said metallic armor 12 may consist of one or more metallic strips helically wound with their convolutions suitably interlocked one with the other, so that a desired degree of flexibility is provided for.

The character of the aforesaid novel combined primary and secondary insulation with 40 which the conductors are provided is such that a very efficient electrical segregation and separation of each conductor or wire as well as a joint insulative shield therefor is assured; the various elements of this insulation structure each contributes in association with the others strong dielectric properties, since the respective materials, viz. rubber, paper and asphaltum are each characterized by the possession of dielectric qualities. The 45 tacky nature of the asphaltum assures both the desired bond between the associated paper wrappings, while nevertheless permitting relative movement between the overlying wrappings when the cable is flexed without 50 risk of the occurrence of ruptures or other separation under bending or pulling strains. The assurance against opening of gaps, breaks, ruptures, perforations or the like is further guaranteed by reason of the relative 55 cross wrapping of the convolutions of the several paper wrappings.

It will be noted that the novel insulation, by reason of the arrangement and relation of the several elements thereof, provides a 60 substantially closely bonded and practically

homogeneous insulation mass, which avoids all necessity for employing comparatively expensive fabric sheaths, and consequently not only is a very efficient insulation provided, but also one which is comparatively inexpensive both from the standpoint of cost of materials, as well as in labor costs involved in its production. 70

It will be understood that while I have described the primary and secondary insulation layers as including but two spirally wound paper wrappings each, it will be nevertheless within the principles and scope of this invention to employ more than two wrappings if it should be considered desirable. 75

Having thus described my present invention, I claim:—

1. As a new article of manufacture, an electric cable having a plurality of wire conductors laid side by side, each conductor having a primary insulation comprising a covering sheath of rubber next thereto, a plurality of paper wrappings spirally wound over said rubber sheath in such manner that the convolutions of one wrapping lie crosswise relative to the convolutions of an underlying wrapping, said wrappings being bonded together and to said rubber sheath by intermediate layers of a non-drying and non-hardening tacky substance; a secondary insulation common to and enveloping the thus primarily insulated conductors, comprising a plurality of enclosing paper wrappings spirally wound thereupon in such manner that the convolutions of one wrapping lie crosswise relative to the convolutions of an underlying wrapping, said enveloping wrappings being also bonded together and to said primary insulation by intermediate layers of a non-drying and non-hardening tacky substance; 90 and an exterior metallic armor applied over all. 100

2. As a new article of manufacture, an electric cable having delivering and returning metallic wires, each wire having a rubber sheath covering the same, a primary paper insulation for each rubber sheathed wire comprising paper strips spirally wound thereon so that the convolutions of the inner strip run in one direction while those of the outer strip run in the opposite direction and thus cross each other, said paper strips being impregnated with and bound together and to the underlying rubber sheath by a non-drying and non-hardening asphaltum, said wires 110 thus primarily insulated being laid together substantially side by side, a secondary paper insulation common to both wires comprising paper strips spirally wound thereover so that the convolutions of the inner strip run in one direction while those of the outer strip run in the opposite direction and thus cross each other, said latter strips being also impregnated with and bound together and the primary insulation by a non-drying and non- 120

hardening asphaltum, said asphaltum in both said primary and secondary insulation permitting relative movement of the paper strips during flexing of the cable without occurrence of gaps or perforations in the insulation, and an exterior metallic armor applied over all.

5 3. In an electric cable, a pair of conductors and insulation therefor comprising, a paper strip wrapped spirally in surrounding relation to each of said conductors, the spirally wrapped paper strips of said conductors extending in the same direction, a coating of non-drying and non-hardening tacky substance surrounding said paper strip wrappings, and an enveloping paper strip applied in common to the laid and wrapped conductors, said enveloping paper strip being wound spirally about said conductors in the reverse direction to the inner paper strip wrappings.

10 15 20 In testimony that I claim the invention set forth above I have hereunto set my hand this 26th day of August, 1926.
